UNITED STATES PATENT OFFICE.

IRVIN J. MAHA, OF SLEEPY EYE, MINNESOTA.

MOTOR-STARTER.

1,389,522.

Specification of Letters Patent. Patented Aug. 30, 1921.

Application filed January 4, 1919. Serial No. 269,613.

To all whom it may concern:

Be it known that I, IRVIN J. MAHA, a citizen of the United States, residing at Sleepy Eye, in the county of Brown and State of Minnesota, have invented new and useful Improvements in Motor-Starters, of which the following is a specification.

This invention relates to motor starters, and particularly to a spring starter for automobile, tractor and similar motors, the object of the invention being to provide simple, reliable and effective means for starting the motor from the spring and rewinding the spring from the power of the motor itself, 10 the starter mechanism including devices for connecting the motor shaft with opposite ends of a coiled starting spring to perform the described functions.

The invention consists of the features of 20 construction, combination and arrangement of parts, hereinafter fully described and claimed, reference being had to the accompanying drawings, in which:—

Figure 1 is a side elevation of the starter 25 mechanism, showing also the adjacent end of the motor shaft.

Fig. 2 is a sectional plan view thereof.

Fig. 3 is a vertical transverse section taken substantially on line 3—3 of Fig. 1.

Fig. 4 is a vertical transverse section taken substantially on line 4—4 of Fig. 1.

Fig. 5 is a plan view showing a modified form of driving means between the motor and starting shafts.

Referring to the drawings, 1 designates the motor shaft and 2 a starter shaft separate from but arranged in axial alinement with the motor shaft. The shaft 2 is journaled in suitable bearing members 3 and 3' 40 upon a U-shaped frame structure 4, and has its inner end arranged in proximity to the outer end of the motor shaft 1. In practice, the frame 4 may be a part of the frame of the vehicle or a separate frame for supporting the starter mechanism, which separate frame may be fastened to the vehicle frame or chassis in any preferred manner. As shown, a clutch device is provided for connecting and disconnecting the shafts 1 and 2, said clutch comprising a tapered friction clutch disk 5 fixed to the shaft 1 and adapted to be engaged by a similar clutch disk 6 feathered to slide upon and rotate with the shaft 2. The clutch member 6 has an annularly grooved hub 7 which fits within a collar 8 upon an adjusting lever 9 pivoted

at one end to the frame 4, said collar being provided with one or more pins 10 engaging the groove of the hub, whereby the clutch member 6 is adapted to rotate with the shaft 2 without interference from the lever 9, but is adjustable longitudinally of said shaft through diverse swinging movements of said lever. A rod 11 connected with the other end of the lever 9 is provided for connection with a suitable control device on the vehicle, whereby the clutch member 6 may be retracted against the resistance of a spring 7^a and adjusted for engagement with the clutch member 5, in which action the spring will assist in advancing the clutch member 6 in an obvious manner. In the present instance I have shown the starting mechanism arranged to transmit motion to the motor shaft in a counter-clockwise direction, but it is to be understood that, dependent upon circumstances or conditions, the starting mechanism may be arranged to transmit motion to the motor shaft in either a clock-wise or a counter-clockwise direction.

The starter comprises a spring starting motor, of the coiled or spiral spring type, the coiled motor spring 12 being arranged within an inclosing drum or casing comprising a pair of spaced disks 13 and 14 and an annular wall 15 carried by one of the disks, in the present instance the disk 13. The wall 15 projects from the peripheral edge of the disk 13 toward and surrounds the peripheral edge of the disk 14, thus forming with said disks an inclosing casing to shield and protect the spring from dust, dirt and the liability of injury.

The disks 13 and 14 are provided with inwardly projecting hubs 16 and 17, which are fitted to turn loosely on the shaft 2 and are held in accurate alinement by an inclosing sleeve 18 and from relative outward movement by collars 19 secured by set screws or other similar means to the shaft 2. The sleeve 18 is fixed, as by suitable fastening means 20, to the hub of the disk 14, but is free for relative rotary movements with respect to the hub of the disk 13. To the sleeve 18, and consequently to the hub of the disk 14, is secured, as indicated at 21, the inner end of the coiled spring 12, the outer end of which is suitably fastened to the inner periphery of the wall 15, as indicated at 22, and hence through said wall to the disk 13.

The disk 13 is employed for transmitting

motion from the spring to the shaft 1 for the purpose of starting the motor, while the disk 14 is employed for transmitting motion from the motor shaft 1 through the shaft 2 for the purpose of rewinding the spring. Formed upon the outer side of the disk 13 is a friction clutch member 23, adapted to be engaged by an adjustable friction clutch member 24, and formed upon the outer face of the disk 14 is a friction clutch member 25 adapted to be engaged by an adjustable clutch member 26. The two clutch members 24 and 26 are normally out of engagement with their companion clutch members 23 and 25, and each of said clutch members 24 and 26 is provided with a hub 27 feathered to slide upon and rotate with the shaft and have a suitable shifting engagement with a collar 28 upon a shifting lever 29, whereby through reverse movements of the lever 29 the adjustable clutch member connected therewith may be shifted into and out of engagement with its companion clutch member upon the drum disk. The levers 29 are pivoted at one end to one side of the frame 4 and are connected at their opposite or free ends for movement in unison by and with a shifter bar 30, the construction being such that longitudinal movement of the shifter bar in opposite directions from a neutral position will throw one of the adjustable clutch members into action and the other out of action, or vice versa. The shifter bar is coupled to a rod 31 leading to a suitable control device (not shown) on the vehicle, whereby said rod may be operated. The lever 29 associated with the clutch member 24 is adapted to retract said clutch member against the resistance of a spring 27, which assists in moving said clutch member into engagement with the clutch member 23.

It will be evident from the foregoing description that the starter shaft 2 may be coupled to the motor shaft 1 for the purpose of either starting the motor from the spring or rewinding the spring from the motor by shifting the clutch member 6 into engagement with the clutch member 5, and that said shaft 2 may be disconnected thereafter from the shaft 1 by retraction of the clutch member 6. Also it will be understood that, assuming the spring 12 to be wound and in readiness for action, a shifting movement of the clutch member 24 into engagement with the clutch member 23 will couple the motor spring to the shafts 1 and 2 for a driving action through an uncoiling motion of the spring, whereby the shaft 1 may be driven for starting the motor. It will be further understood that by coupling the shafts 1 and 2 and throwing the clutch member 26 into engagement with the clutch member 25, motion may be transmitted from the shaft 1 to the shaft 2 to effect the rewinding of the spring 12 in an obvious manner.

In order to permit rotation of the disk 14 in the proper direction to wind the spring 12, while holding said disk from retrograde motion, a suitable pawl and ratchet mechanism is provided consisting of ratchet teeth 70 32 upon the outer side of the clutch member 25 engaged by a spring actuated dog or pawl 33 on the frame 4, the construction being such that the dog will permit the disk to have rewinding motion, in which action the 75 dog slides over the inclined faces of the ratchet teeth, the dog engaging the shoulders of the teeth to lock the disk against reverse motion. Also in order to hold the disk 13 from rotation under the action of the spring, 80 until it is desired to utilize the power of the spring for a motor starting action, a brake device is provided for engaging and releasing said disk. This brake device comprises a friction brake band 34 fixed at one end to 85 the frame 4, as at 35, and connected at its opposite end on the inner arm 36 of a bell crank lever 37 pivotally mounted on the frame 4, the opposite arm 38 of which lever carries a cam roller 39. The brake strap 34 surrounds and engages the wall 15, which thus serves as a friction brake surface, the strap when tightened holding the disk 13 from rotation while the spring is being wound and until its motor starting action is 90 desired, the release of the brake band permitting the spring to unwind and transmit 95 rotary motion to the disk 13.

For the purpose of normally maintaining the friction band in engagement with the surface 15 at all times in the neutral position of the parts shown in Fig. 2, and during the adjustments of the rewinding clutch member 26, while effecting an automatic release and tightening of the brake band in the in 100 and out adjustments of the clutch device 24, the bar 30 is suitably constructed to control the bell crank lever 37 for brake tightening and releasing actions. To this end, the bar is provided with plane surfaces 40 and 41 arranged at different elevations and connected by an intervening inclined or cam surface 42, upon which surfaces the roller 39 is adapted to ride. The roller 39 normally engages the surface 40, with which it is in contact when the parts are in the neutral position shown in Fig. 2 and also in the adjustment of the clutch member 26 into position for the rewinding action, whereby the bell crank lever 37 is held in brake band applying 105 position. When, however, the bar 30 is shifted forwardly to the degree necessary to move the clutch member 24 into engagement with the clutch member 23 the roller 39 travels down the inclined surface 42 and engages 110 the surface 41, thus allowing the bell crank lever to be depressed by the action of a spring 43 to release the brake band, thus permitting the disk 13 to be driven by the unwinding action of the spring 12 to transmit 115 120 125 130

motion to the shaft 2 for a motor starting action.

In Fig. 5 of the drawing I have shown a modification in the driving connection between the motor shaft 1^a and starter shaft 2^a which may be employed when it is necessary to dispose these two shafts at a right angle or other angles to each other, as is necessary in the application of the invention to some forms of tractors or trucks. As herein shown, a gear 5^a, feathered to slide upon and rotate with the shaft 1^a, is provided in lieu of the disk 5, and this gear meshes with a gear 6^a on the shaft 2^a, the gear 5^a being adapted for coöperation with a shifting device to throw it into and out of engaging relation. The shaft 2^a as shown is composed of sections united by a universal or other similar joint 6^b, thus allowing the gears to mesh while the shafts operate at different working angles as will be readily understood.

As shown, the springs 7^a and 27^a are arranged to bear against collars 7^b and 27^b fixed to the shaft 2 on opposite sides of the bearing 3', and said springs also bear against the sleeves 7 and 27 of the respective clutch members 6 and 24. Thus it will be understood that these springs are normally held under tension when the clutch members are retracted and upon the release of said clutch members act positively to move the adjustable clutch members into clutching engagement with the coacting clutch members 5 and 23. The springs are of advantage in maintaining the clutch elements in engaging relation without the necessity of exerting objectionable pressure on the clutch collars, and the use of the spring 27^a, in addition, is advantageous in that, by holding the clutch member 24 in positive engagement with the clutch member 23, the necessity of a bearing motion for this purpose from the collar 28 to the collar 27 is avoided, thus doing away with a large amount of friction and resistance to the action of the spring 12 in a motor starting operation.

While I have specified the use of friction clutches, it is to be understood that any equivalent type of clutches may be employed in lieu thereof.

Having thus fully described my invention, I claim:—

1. In a device of the class described, an engine shaft, a starter shaft, a clutch mechanism between said shafts, a two-part motor casing the parts thereof being mounted for independent rotation on said starter shaft and with respect one part to the other, a coiled power spring within said motor casing and connecting the parts thereof, a clutch mechanism coöperative with each part of said motor casing and said starter shaft, interconnected means for simultaneously actuating said last mentioned clutch mecha-

nisms for the alternate connecting and disconnecting of the parts of said motor casing to and from said starter shaft, a pawl and ratchet mechanism for holding one of the parts of said motor casing against retrograde movement during the rewinding of said coiled power spring, and a brake band encircling the other of said parts of said motor casing for holding the part against rotation during the rewinding of said coiled power spring and releasing the said part for the uncoiling of said power spring, said brake band being actuated by said interconnected means simultaneously with the actuation of said last mentioned clutch mechanisms. 80

2. In a device of the class described, an engine shaft, a starter shaft, a clutch mechanism between said shafts, a two-part motor casing the parts thereof being mounted for independent rotation on said starter shaft and with respect one part to the other, a coiled power spring within said motor casing and connecting the parts thereof, a clutch mechanism coöperative with each part of said motor casing and said starter shaft, 90 a pawl and ratchet mechanism for holding one of the parts of said motor casing against retrograde movement during the rewinding of said coiled power spring, a brake band encircling the other of said parts of said motor casing for holding the part against rotation during the rewinding of said coiled power spring and releasing the said part for the uncoiling of said power spring, levers for actuating said last mentioned clutch mechanisms, a bar connecting said levers and operable for alternately connecting and disconnecting the parts of said motor casing to said starter shaft through said clutch mechanisms, and means actuated by said bar 105 for the operation of said brake band.

3. In a device of the class described, an engine shaft, a starter shaft, a clutch mechanism between said shafts, a two-part motor casing the parts thereof being mounted for independent rotation on said starter shaft and with respect one part to the other, a coiled power spring within said motor casing and connecting the parts thereof, a clutch mechanism coöperative with each part 110 of said motor casing and said starter shaft, a pawl and ratchet mechanism for holding one of the parts of said motor casing against retrograde movement during the rewinding of said coiled power spring, a brake band 120 encircling the other of said parts of said motor casing for holding the part against rotation during the rewinding of said coiled power spring and releasing the said part for the uncoiling of said power spring, levers for actuating said last mentioned clutch mechanisms, a bar connecting said levers and operable for alternately connecting and disconnecting the parts of said motor casing to said starter shaft through said clutch 130

mechanisms, and a bell-crank lever connected to one end of said brake band, said bell-crank lever being actuated by said bar for the operation of said brake band simultaneously and correspondingly with the operation of said last mentioned clutch mechanisms.

4. In a device of the class described, an engine shaft, a starter shaft, a clutch mechanism between said shafts, a two-part motor casing, the parts thereof being mounted for independent rotation on said starter shaft and with respect one part to the other, a coiled power spring within said motor casing and connecting the parts thereof, a clutch mechanism coöperative with each part of said motor casing and said starter shaft, a pawl and ratchet mechanism for holding one of the parts of said motor casing against retrograde movement during the rewinding of said coiled power spring, a brake band encircling the other of said parts of said motor casing for holding the part against rotation during the rewinding of said coiled power spring and releasing the said part for the uncoiling of said power spring, levers for actuating said last-mentioned clutch mechanisms, a bar connecting said levers and operable for alternately connecting and disconnecting the parts of said motor casing to said starter shaft through said clutch mechanisms, a cam surface formed with said bar, and a bell-crank lever connected to one end of said brake band, said bell-crank lever being actuated by the cam surface of said bar for the operation of said brake band simultaneously and correspondingly with the operation of said last mentioned clutch mechanisms.

40 5. In a device of the class described, an engine shaft, a starter shaft, a clutch mechanism between said shafts, a two-part motor casing, the parts thereof being mounted for independent rotation on said starter shaft and with respect one part to the other, a coiled power spring within said motor casing and connecting the parts thereof, a clutch mechanism coöperative with each part of said motor casing and said starter shaft, a pawl and ratchet mechanism for holding one of the parts of said motor casing against retrograde movement during the rewinding of said coiled power spring, a brake band encircling the other of said parts of said motor casing for holding the part against rotation during the rewinding of said coiled power spring and releasing the said part for the uncoiling of said power spring, levers for actuating said last mentioned clutch mechanisms, a bar connecting said levers and operable for alternately connecting and disconnecting the parts of said motor casing to said starter shaft through said clutch mechanisms, said bar having one of its faces formed to provide plane surfaces one of a greater height than the other and interconnected by an inclined surface at a point intermediate the opposite ends of the same, a bell-crank lever connected to one end of said brake band, and a roller journaled on the free end of said bell-crank lever and bearing on the plane surfaces of said bar, said bell-crank lever being actuated by said bar for the operation of said brake band simultaneously and correspondingly with the operation of said last mentioned clutch mechanisms.

said coiled power spring and releasing the said part for the uncoiling of said power spring, levers for actuating said last mentioned clutch mechanisms, a bar connecting 60 said levers and operable for alternately connecting and disconnecting the parts of said motor casing to said starter shaft through said clutch mechanisms, a bell-crank lever connected to one end of said brake band, 65 and a roller journaled in the free end of said bell-crank lever and bearing on the cam surface of said bar, said bell-crank lever being actuated by said bar for the operation of said brake band simultaneously and correspondingly with the operation of said last 70 mentioned clutch mechanisms.

6. In a device of the class described, an engine shaft, a starter shaft, a clutch mechanism between said shafts, a two-part motor 75 casing, the parts thereof being mounted for independent rotation on said starter shaft and with respect one part to the other, a coiled power spring within said motor casing and connecting the parts thereof, a 80 clutch mechanism coöperative with each part of said motor casing and said starter shaft, a pawl and ratchet mechanism for holding one of the parts of said motor casing against retrograde movement during the rewinding 85 of said coiled power spring, a brake band encircling the other of said parts of said motor casing for holding the part against rotation during the rewinding of said coiled power 90 spring and releasing the said part for the uncoiling of said power spring, levers for actuating said last mentioned clutch mechanisms, a bar connecting said levers and operable for alternately connecting and disconnecting the parts of said motor casing to said starter 95 shaft through said clutch mechanisms, said bar having one of its faces formed to provide plane surfaces one of a greater height than the other and interconnected by an inclined surface at a point intermediate the 100 opposite ends of the same, a bell-crank lever connected to one end of said brake band, and a roller journaled on the free end of said bell-crank lever and bearing on the plane surfaces of said bar, said bell-crank lever 105 being actuated by said bar for the operation of said brake band simultaneously and correspondingly with the operation of said last mentioned clutch mechanisms.

In testimony whereof I affix my signature. 110

IRVIN J. MAHA.
